(57) CLAIM

The ornamental design for a display screen with a graphical user interface, as shown and described.

DESCRIPTION

FIG. 1 is a front view of a display screen with a graphical user interface in accordance with our design; and, FIG. 2 is a front view of a display screen with a graphical user interface in accordance with our design.

The broken line showing a portion of the display screen in all views forms no portion of the claimed design.
